Specification for Design.

Patented Nov. 26, 1912.

Application filed August 26, 1912. Serial No. 717,227. Term of patent 3½ years.

To all whom it may concern:

Be it known that I, FRED S. BERNSTEIN, a citizen of the United States, residing at Chicago, in the county of Cook and State of Illinois, have invented a new, original, and ornamental Design for Advertising-Sign Structures, of which the following is a specification, reference being had to the accompanying drawing, wherein I have shown my new design.

Figure 1 shows a front elevation of the advertising sign structure and Fig. 2 a side elevation thereof.

I claim:

The ornamental design for an advertising sign structure as shown.

FRED S. BERNSTEIN.
